UNITED STATES PATENT OFFICE.

JOHN F. WOLLENSAK, OF CHICAGO, ILLINOIS.

DESIGN FOR A BATTERY-CARBON.

SPECIFICATION forming part of Design No. 19,999, dated July 1, 1890.

Application filed April 14, 1890. Serial No. 347,908. Term of patent 14 years.

To all whom it may concern:

Be it known that I, JOHN F. WOLLENSAK, a citizen of the United States, residing at Chicago, Illinois, have invented a certain new 5 and original Design in Battery-Carbons, of which the following is a specification.

My invention consists in the form, configuration, and design of a battery-carbon, hereinafter described and claimed.

10 In the drawings Figure 1 is a perspective view of my improved carbon; and Fig. 2 is a plan of a horizontal section of the carbon, taken through the corrugated portion.

15 The leading feature of my design for battery-carbons comprises a body of an oval, ob-

long, or cylindrical shape, with a number of channels or grooves upon its outer surface arranged longitudinally thereon. These channels or grooves distinguish my design of carbon in shape, configuration, and appearance 20 from any that have been heretofore made or used.

What I regard as new, and desire to secure by Letters Patent, is—

The design for a battery-carbon, substantially as herein shown and described.

JOHN F. WOLLENSAK.
